UNITED STATES PATENT OFFICE.

AMOS G. FITZ, OF AUBURN, MAINE, ASSIGNOR TO FITZ DOUBLE PIVOT LAST COMPANY, OF AUBURN, MAINE, A CORPORATION OF MAINE.

LAST.

No. 913,118.

Specification of Letters Patent.

Patented Feb. 23, 1909.

Application filed August 24, 1908. Serial No. 449,892.

To all whom it may concern:

Be it known that I, AMOS G. FITZ, a citizen of the United States, residing at Auburn, in the county of Androscoggin and 5 State of Maine, have invented new and useful Improvements in Lasts, of which the following is a specification.

It is a common custom for retail shoe dealers, traveling salesmen and others employed in the sale of shoes to place in the shoe a follower, the top or exposed portion of which is covered with silk, satin, embossed leather or other material to add to the attractiveness of the shoe. Lasts or followers connected by a pivoted union as at 10 present constructed are not well adapted for this purpose because of the fact that the line of division is so far toward the heel part that it comes in the portion of the last 15 which is exposed in a low shoe like the Oxford tie.

The object of my invention is to provide a full formed last with a line of division extending so far forward that the entire 20 portion of the last exposed will be unbroken. To this end I divide the last on lines of cut beginning at a point in the waist portion of the last at or about coincident with the bottom of the front opening in the shoe, when 25 the last is inserted therein; thence extending rearwardly and downwardly to the bottom of the last at a point at or near the instep. The line of division may be a double curved line partly convex and partly concave as 30 shown in Figure 1, one or more straight lines as shown in Fig. 2, or one or more concave lines in the fore part as shown in Fig. 3, all of which as well as many others are within the spirit and scope of my invention.

In the drawing herein accompanying and making part of this application, Fig. 1 is a longitudinal vertical sectional view of a hollow last embodying my invention. Fig. 45 2 is a side elevation of a last and shoe with parts of the shoe and parts of the last broken away to show the construction thereof of showing a different line of division and Fig. 3 is a side elevation of a last showing 50 still another line of division.

In said drawings A represents the heel part of a last, B the fore part and C a union connecting the parts, the union being of such a character as will permit the fore

part of the last to be raised upwardly and 55 rearwardly, the front portion of the heel part pivoting and sliding on the rear inclined surface of the fore part.

In Fig. 1 the dotted lines show the movement of the heel part when about to be inserted in or in being removed from the shoe, the point D of the heel part sliding up on the inclined surface E on the fore part, the flexible cord holding the parts in yielding engagement during the insertion or removal 60 of the heel part.

In Fig. 2 a solid last is shown inserted in a shoe to illustrate its position and operation in the shoe. In this case the shoe has the usual front opening G extending down to 70 the point G' and has the usual tongue H inserted in said opening. The last is divided on a line of cut beginning at or about the point G' extending downwardly and rearwardly as seen at J.

Fig. 3 shows a broken line of division both concave in the fore part.

When the last is divided in the manner hereinbefore mentioned the line of division is entirely concealed within the shoe and the 80 exposed part whether finished in the natural wood or covered with an ornamental covering, is unbroken. In all cases the front end of the heel part turns upwardly and backwardly away from the fore part which so far 85 as I am aware is an entirely new feature in the construction of lasts and renders it well adapted for other uses than that herein specified. The line of cut beginning at the 90 waist of the last and thence extending rearwardly and downwardly to the bottom of the last and the union between the two parts, whereby the lower front portion of the heel part is caused to slide and pivot on the lower rear portion of the fore part are also exceeding 95 valuable features of my invention as is also the broken line of division whether straight or curved.

Having thus described my invention and its use I claim:

1. A last divided on a line beginning in front of the highest part and thence extending rearwardly and downwardly and a union pivotally connecting the parts, whereby the front end of the heel part can be turned upwardly and rearwardly away from the fore part.

2. A last divided on a line beginning at

the waist and thence extending rearwardly and downwardly and a union pivotally connecting the parts, whereby the front end of the heel part can be turned upwardly and rearwardly away from the fore part.

3. A last divided on a broken line beginning at the waist portion and thence extending rearwardly and downwardly and a union pivotally connecting the parts, whereby the front end of the heel part can be turned upwardly and rearwardly away from the fore part.

4. A last divided on a line beginning at the waist of the last and thence extending rearwardly and downwardly, said line of division being composed of a plurality of curves, and a union pivotally connecting the parts, whereby the front end of the heel part

can be turned upwardly and rearwardly away from the fore part.

5. A last of standard shape divided on a line beginning at the waist and thence extending rearwardly and downwardly and a union pivotally connecting the parts, whereby the front end of the heel part including a portion of the waist can be turned upwardly and rearwardly away from the fore part.

In testimony whereof, I have signed my name to this specification in the presence of two subscribing witnesses this nineteenth day of August, 1908.

AMOS G. FITZ.
